UNITED STATES PATENT OFFICE.

ANDREW L. HENRY AND GILES S. MOORE, OF INDIANAPOLIS, INDIANA, ASSIGNORS TO TROLLEY SHOE WHEEL COMPANY, OF INDIANAPOLIS, INDIANA, A CORPORATION OF INDIANA.

TROLLEY.

Application filed August 3, 1925. Serial No. 47,893.

Our said invention relates to a trolley and it is an object of the same to provide a device of this character with a shoe taking the place of the usual wheel, said shoe being mounted to float on a pivot on the trolley-pole, and being so formed that it will maintain the same balanced relation on the pole at all times regardless of the extent of abrasion of the shoe by the friction of the wire.

Another object is to improve the means for conducting current from the wire through the trolley.

A further object of the invention is to provide improved means for limiting the swing of the trolley when the trolley is off the wire from any cause.

Referring to the accompanying drawings, which are made a part hereof and on which similar reference characters indicate similar parts,

Figure 1 is a side elevation of our device in one position of use,

Figure 2, a side elevation in another position, and

Figure 3, a section on line 3-3 of Fig. 1.

In the drawings reference character 10 indicates a harp having forks 11 with lugs 11' hereinafter described. Such harp may be of any ordinary or conventional character or of any desirable construction adapted to cooperate with the features of our improved trolley. A pin 12 passes through bearings at the upper end of the trolley harp and is secured in place in any convenient manner this pin providing a bearing for the trolley, which has side flanges 13 forming a groove between them. In the position shown in Figure 1 the groove provides a shoe having a straight face at 14 which face is horizontal in Figure 1, i. e. during forward movement of the trolley.

In the operation of trolley shoes it is important that the relationship between the fulcrum or point of contact between the wire and shoe maintain a fixed relation to the axis of the shoe so that regardless of the wear in use the balance of the shoe on its axis will be maintained uniform.

To accomplish this result we determine the point on the wearing face of the shoe at which this fulcrum should be maintained in order to produce the best results and then at this point cut an aperture through the shoe forming a shoulder with a straight ver-

tical face 15 adjacent to the axis so that as the bearing face wears down the point of the fulcrum will be maintained. This aperture also serves as a means for ready clearance of the wearing face of the shoe from accumulations of dirt, ice, snow, etc., which readily fall through and thus are quickly removed from interfering with the contact and the operation.

The face 15 is further useful in that it provides a convenient means for viewing the shoe to determine the amount of wear. A mark on this face may be so placed as to serve to indicate the time when the old shoe should be replaced by a new one, i. e. when the shoe is worn down to such mark. Such a mark would easily be seen from the rear, the trolley pole being pulled down if necessary.

The flanges 13 are continued around at least two sides of the trolley which is roughly circular with flattened parts providing three or four sides approaching the form of a trapezium. At a side of the trolley adjacent to the face 14 these flanges form a sort of bridge comprising a groove with a bottom face 18 along which the wire rides to a wheel 19 during reverse movement of the trolley and the car by which it is carried, as indicated in Figure 2. The wheel 19 and the bridge 18 are arranged to touch the wire at the same time in backing up, the working faces at 18 and on the wheel being in line with each other.

A pair of narrow bracing portions indicated at 20 and 20' connect the part of the trolley adjacent the wheel 19 to the part at the left end of the shoe 14 in Figure 1, these portions forming the third and fourth sides of a device which, as a whole is nearly rectangular, or specifically trapezoidal, in shape. These parts may be slender and light to limit the weight of the trolley. The brace 20 is forked adjacent the wheel, the forks corresponding to the flanges 13, and the forks are perforated to provide bosses 21 for the fixed pivot 22 of the wheel 19. In the normal position of the trolley these bosses lie near to but out of contact with the trolley harp but should the trolley get off the wire the lugs 21' on the bosses can act to limit the swinging movement of the trolley in one direction by striking against lugs 11 on the trolley forks. Stops 23 are

provided at opposite sides of the trolley to limit the movement of the same in the contrary direction, the location of the stops 23 being at the opposite extreme position of the 5 harp from the position where the lugs 21' contact with it.

The trolley has a flat faced central bearing portion at 24 through which the pin 12 passes, and copper plates 25 are riveted to 10 said pin by copper rivets 26, said plates bearing against the forks 11 of the harp with their outer faces. This construction insures permanent electrical contact of the trolley and the harp, and thus provides for an uninterrupted flow of current. To save material and to make the trolley as light as possible, the frame of the trolley is skeletonized so far as possible, as by providing 15 narrow ribs 27, 28 and 29 while leaving the intervening space open. These ribs connect the trolley bearing 24 respectively to the side piece 20', the bridge 18 and the shoe 14 and each rib is at right angles to its side of the trolley, while ribs 27 and 29 are nearly 20 alined when in normal position. In a preferred construction there are diverging ribs 25 29 merging into the flanges 13 and 14, but this and other details are subject to variations in accordance with the purposes of our 30 invention.

It will be obvious to those skilled in the art that various changes may be made in our device without departing from the spirit of the invention and therefore we do not limit 35 ourselves to what is shown in the drawings and described in the specification, but only as indicated in the appended claims.

Having thus fully described our said in-

vention what we claim as new and desire to 40 secure by Letters Patent is:

1. In a trolley, an approximately rectangular structure comprising a shoe bearing against the wire during movement in one direction, a wheel engaging the wire during 45 movement in the reverse direction, a bearing therefor, a bridge between the wheel and the shoe also engaging the wire during such reverse movement, a harp, a pin carried by the harp, a bearing on the trolley for said pin, and skeletonized supporting means for 50 such parts including relatively slender side members connecting the wheel bearing with said shoe, and relatively slender cross ribs connecting the wheel bearing respectively to the shoe the bridge and one or more of said slender side members, substantially as set forth.

2. A trolley as in claim 1 having lugs extending inward from said wheel bearings, and lugs on the harp engaging the first-named lugs to limit oscillation of the trolley 55 in one direction, substantially as set forth.

3. A trolley as in claim 1, the sides of the shoe overhanging the adjacent parts of the harp, lugs on the trolley normally covered by said overhanging parts, and abutments on the harp for engagement by the first-named lugs to limit oscillation of the trolley 65 in one direction, substantially as set forth.

In witness whereof, we have hereunto set 70 our hands and seals at Indianapolis, Indiana, this 1st day of August, A. D. nineteen hundred and twenty-five.

ANDREW L. HENRY. [L. S.]
GILES S. MOORE. [L. S.]
